The design of the removable front draught and hearth-plate A, in said photograph, consists essentially of the border-moulding b and corner ornaments c, on the upright part, and the radial angle-ornaments d, scrolls e, and circular mouldings f, on the swelling, register-holding portion of said plate, all shaped and arranged as shown in the said photograph.

The design of the plate or leg G consists of the particular ornamental shape and configuration of that part, as shown in said photograph.

The design of the plate H consists of the row of ornamental forms i around the bottom of the raised portion j, all shaped as represented in the photograph.

The design of the main front plate K consists, essentially, of the row of ornaments l, along the flaring top portion, the tablets m and n, the capitals o o, and the ornamental panels p, q q, r r, and columns s s, s s, all shaped and disposed as shown by said photograph; and the design of the folding doors T T' consists of the panel-mouldings u u, tablets v, and panel-ornament w, shaped and arranged as shown.

What we claim as our invention or production, and desire to secure by Letters Patent, is—
